(57) **CLAIM**

The ornamental design for a fairing with flow channels, as shown and described.

DESCRIPTION

FIG. 1 is a top, front, left perspective view of a fairing with flow channels according to our new design;

FIG. 2 is a left side elevation view thereof;

FIG. 3 is a right side elevation view thereof;

FIG. 4 is a front elevation view thereof;

FIG. 5 is a rear elevation view thereof;

FIG. 6 is a top plan view thereof; and,

FIG. 7 is a bottom plan view thereof.

The broken lines illustrate portions of the fairing with flow channels that form no part of the claimed design. The dash-dot-dot line broken lines define a boundary of the claimed design and form no part thereof.

1 Claim, 4 Drawing Sheets
